UNITED STATES PATENT OFFICE.

HARRY R. BARTELL, OF ST. LOUIS, MISSOURI, ASSIGNOR TO COMMONWEALTH STEEL COMPANY, OF ST. LOUIS, MISSOURI, A CORPORATION OF NEW JERSEY.

LOCOMOTIVE FRAME.

Application filed December 1, 1924. Serial No. 753,294.

To all whom it may concern:

Be it known that I, HARRY R. BARTELL, a citizen of the United States, residing at St. Louis, Missouri, have invented a certain new and useful Improvement in Locomotive Frames, of which the following is a specification, such as will enable others skilled in the art to which it appertains to make and use the same.

This invention relates to new and useful improvements in locomotive frames or beds and the objects of the invention are to provide a locomotive bed having valve gear brackets or supports formed integral with the side members thereof, thereby insuring accurate location of said brackets and eliminating the use of attaching means therefor and the machining of the parts.

Further objects of the invention are to provide a locomotive bed cast in a single piece and comprising side members and transverse and end members and valve gear brackets formed integral with and extending laterally from said side members and adapted to receive and support the valve gear mechanism.

With the foregoing and other objects in view my invention consists in certain novel features of construction and arrangement of parts hereinafter more fully described and claimed, and illustrated in the accompanying drawings, in which—

Figure 1 is a top plan view of the locomotive bed.

Figure 2 is a side elevation thereof.

Figure 3 is an enlarged plan view of the forward portion of the locomotive bed.

Figure 4 is a side elevation thereof and showing in dotted lines the reverse shaft arm and the like and parts associated therewith.

Figure 5 is a cross sectional view taken on lines 5—5 of Figure 3 and showing in full lines the reverse shaft arm and shaft.

Figure 6 is a cross sectional view taken on line 6—6 of Figure 3.

Figure 7 is a fragmental plan view of a modified form of locomotive bed.

Figure 8 is a side elevation thereof.

Heretofore the brackets or supports supporting the valve gear mechanism were made separate from the locomotive bed and were secured thereto by suitable attaching means. This required machining of the bed as well as the parts to be attached

thereto and called for accurate assembly of the parts in position. In the present invention the valve gear supports are cast integral with the side members of the locomotive bed, thereby eliminating time and labor involved in machining and attaching the supports to the bed and providing a strong and durable construction.

Referring by numerals to the accompanying drawings, 10 indicates a locomotive bed cast in a single piece and consisting of longitudinally disposed side members 11 connected at suitable intervals by transverse members 12 and terminating in a rear end 14 and a front end 15. The locomotive bed can be of any approved design and the various members thereof are of any desired cross section.

Extending outwardly from side members 11 at the appropriate points are horizontally disposed brackets 16 which are preferably box-shaped in cross section, as shown in Figure 6, and are provided at their point of junction with the side members 11 with horizontally disposed flanges 17 which reinforce said brackets. Brake hangers 18 are formed on side members 11 below brackets 16 and are provided with flanges 19 which extend upwardly and merge with the lower faces of said brackets. The upper face of each bracket is provided with a pad 20 which forms a seat and serves as a point of attachment for a reverse shaft bearing 21. (See Fig. 4.) A shaft 22 operates in bearing 21 and carries a reverse shaft arm 24 which is operated in the usual manner and is connected at one end to a link 25 of the valve gear mechanism. The reverse shaft arm 24 and link 25 and their operative connections are of any standard design and need not be described here in detail.

Integrally formed with the outer end of each bracket 16 is a pair of spaced rails 26 which are horizontally disposed and extend longitudinally of the bed. The forward ends of these rails converge toward each other and are connected to the outer end of a transversely disposed front rail 27 which extends laterally from the locomotive frame. Lugs 28 having preferably bushed bearing apertures 29 are formed integral with rails 26 and are aligned and form bearings for the shaft of link 25.

In the modified form shown in Figures 7 and 8 a bracket 30 extends laterally from

each side member 11^a and has a pad 31 for receiving the bearing of a reverse shaft arm 32. A yoke 34 is also formed integral with bracket 30 and is provided with lugs 35 which form a support for the shaft of a link 36.

A locomotive frame of my improved construction is arranged so as to provide ample space and operating clearance for the locomotive parts and mechanisms thereof and to accommodate the various operating connections therefor.

It is obvious that minor changes in the size, form and construction of the various parts of my improved frame can be made and substituted for those herein shown and described, without departing from the nature and scope of my invention.

I claim:

- 20 1. A locomotive frame formed in a single piece and comprising side members, a series of transverse members, and brackets extending from said side members for supporting valve gear mechanism.
- 25 2. A locomotive bed cast in a single piece and comprising side members, a series of transverse members, and reverse gear brackets extending laterally from said side members.
- 30 3. A locomotive bed cast in a single piece and comprising side members, a series of transverse members uniting said side members, and brackets extending laterally from said side members and adapted to receive reverse gear bearing.
- 35 4. A locomotive bed provided with reverse gear brackets cast integral with the side members thereof.
- 40 5. A locomotive bed provided with lateral

extensions formed integral therewith and adapted to support the valve gear mechanism.

6. A locomotive bed having side members provided with integral valve gear brackets.

7. A locomotive bed having side members provided with integral reverse gear brackets.

8. A locomotive bed having side members provided with integral brake hanger bearings and reverse gear brackets.

9. A locomotive bed having side members provided with integral bearings for the link shaft of the valve gear.

10. A locomotive bed having side members provided with integral supports for the link of the valve gear.

11. A locomotive bed cast in one piece and provided with integral link supports.

12. A locomotive bed cast in one piece and provided with integral reverse gear brackets.

13. A locomotive bed cast in a single piece and provided with integral reverse gear brackets and link supports.

14. A locomotive bed cast in a single piece and having laterally disposed brackets and pads on said brackets serving as seats and points of attachment for the reverse arm bearings.

15. A locomotive bed cast in a single piece and provided with integral brackets, pads on said brackets for receiving the reverse gear bearings, and link bearings formed integral with said brackets.

In testimony whereof I hereunto affix my signature this 25 day of November, 1924.

HARRY R. BARTELL.
